(57) **CLAIM**

The ornamental design for a junction box mount for a modular sensor system as shown and described.

DESCRIPTION

FIG. 1 is a top perspective view of a first embodiment of a junction box mount for a modular sensor system showing our new design;

FIG. 2 is a bottom perspective view thereof;

FIG. 3 is a left side view thereof;

FIG. 4 is a right side view thereof;

FIG. 5 is a back view thereof;

FIG. 6 is a front view thereof;

FIG. 7 is a top view thereof;

FIG. 8 is a bottom view thereof;

FIG. 9 is a top perspective view of a second embodiment of the junction box mount for a modular sensor system showing our new design;

FIG. 10 is a bottom perspective view thereof;

FIG. 11 is a left side view thereof;

FIG. 12 is a right side view thereof;

FIG. 13 is a back view thereof;

FIG. 14 is a front view thereof;

FIG. 15 is a top view thereof; and,

FIG. 16 is a bottom view thereof.

The portions of the drawings shown in broken lines define the bounds of the claimed design and form no part of the claimed design.
